UNITED STATES PATENT OFFICE.

SIDNEY A. REEVE, OF WORCESTER, MASSACHUSETTS, ASSIGNOR TO CHARLES F. BROWN,
TRUSTEE, OF READING, MASSACHUSETTS.

COMPOUND INTERNAL-COMBUSTION ENGINE.

No. 926,134.

Specification of Letters Patent.

Patented June 29, 1909.

Application filed June 30, 1905. Serial No. 267,718.

To all whom it may concern:

Be it known that I, SIDNEY A. REEVE, of Worcester, in the county of Worcester and State of Massachusetts, have invented certain new and useful Improvements in Compound Internal - Combustion Engines, of which the following is a specification.

This invention relates to compound internal-combustion engines, and its general objects are to increase the efficiency thereof and the flexibility of regulation. To this end I adopt the compound type and provide for a greater range of pressures than has heretofore been known in these engines, as well as certain novel expedients for insuring the correct proportioning and regulation of air and fuel, proper working under varying load, and transmission of working fluid from the high-pressure motor to the low-pressure motor with a minimum heat-loss.

In order to coördinate the functions of the principal elements making up the engine, under varying loads, I prefer to provide a system of regulation by which the power of the combustion-motor, represented in its discharged gases, and the mechanical power of the low-pressure motor, are subjected to a joint control, which may take the form of an automatic governor responsive to the load on the low-pressure motor, or to the load on both motors when the two drive the same shaft.

My invention in one of its forms, involves the disconnection of the low-pressure motor from the high-pressure motor so that the two may run at relatively-varying speeds. Such an arrangement has advantages for certain classes of work. It enables the low-pressure motor to be located at some distance from the high-pressure motor and to that end the reduction of the excess temperature of the hot gases discharged under pressure from the high-pressure motor, by generating steam with a stable degree of superheat, automatically maintained, is of peculiar utility, since it prevents any large loss of heat in transmission of the working fluid through a conduit of considerable length. The disengaged arrangement also possesses great flexibility in running, for the low-pressure motor will call for greater or less quantities of fluid according to the work which it has to perform, and the high-pressure motor may be regulated to supply this demand, independently of the speed of the low-pressure motor. At

times the compressing department may furnish an excess of compressed air over what is needed for combustion, and I provide an arrangement for automatically disposing of such excess in a useful manner.

Of the accompanying drawings illustrating an embodiment of my invention,—Figure 1 represents a diagrammatic view of the apparatus. Fig. 2 represents a plan-view. Fig. 3 represents a rear elevation with the cooling chamber in section. Figs. 4 and 5 represent sections on the lines 4—4 and 5—5 of Fig. 2. Fig. 6 represents a side elevation of the compressor. Fig. 7 represents a detail section of one of the spraying devices. Fig. 8 represents a side elevation partly in section showing a modification in which the high-pressure and low-pressure engine run at independent speeds. Fig. 9 represents a view showing a section of the cooling-chamber in the modification and an elevation of the low-pressure engine which here takes the form of a turbine. Fig. 10 represents a plan view of the modification. Fig. 11 represents a section of the turbine throttle. Fig. 12 represents a section of one of the pressure diaphragms.

The same reference characters represent the same parts in all the figures.

Referring at first to the form shown in Figs. 1 to 7 inclusive, 20 indicates a shaft having three cranks 21, 22, 23, to which are attached respectively the connecting-rods of the high-pressure engine 24, the low-pressure engine 25 and the compressor 26, the latter having an air-compressing cylinder 27 and a gas-compressing cylinder 28 whose pistons are attached to the same piston rod. Fig. 1 of the drawings shows in diagram the arrangement of the parts, and for the sake of greater clearness, certain of the mechanism such as the link-motion, is turned over into the same plane with the main shaft.

The motor here represented for purposes of illustration, is in a general way, of the compressor-charged Lenoir-cycle type and its high-pressure engine 24 is of a form more particularly described in my Patent No. 899,842, but as here shown it includes a cylinder 29, piston 30, admission-valves 31, exhaust-valves 32 and igniters 33, the valves and igniters being duplicated at either end so that the engine is rendered double-acting.

From the air- and gas-compressors 27 and 28, the high-pressure cylinder 29 receives compressed charges of air and gas through

pipes 34, 35, which fluids become mixed in passing the admission-valves and are admitted during the first portion of the working stroke of the piston 30. Ignition and cut-off occur at a predetermined point in the stroke, the pressure increases by explosion, and expansion of the charge takes place during the latter part of the stroke. At the end of the stroke the exhaust-valve 32 opens and the products of combustion pass through a pipe 36 in the cooling-chamber 37 and thence into the cylinder 38 of the low-pressure engine 25 wherein they perform work on the piston 39 of said low-pressure engine.

15 Rotation of the shaft 20 is counter-clockwise, and the compressor-crank 23 is set at an angle of about 40° behind the high-pressure engine crank 21 in order to properly charge the high-pressure cylinder.

20 I have shown a modified radial valve-gear adapted to an engine of this type and also to other engines, but may use other forms of valve-motion. This valve-gear dispenses with eccentrics and utilizes the motion of the 25 differently-timed cross-heads of the high and low-pressure cylinders. From the cross-head 40 of the high-pressure cylinder motion is taken by a pin 41 and rod 42 to a floating-lever 43 connected with the admission and 30 exhaust valves 31 and 32 of cylinder 24. This connection is by way of rod 44, rock-shaft 45, and rockers 46, 47, 48, 49 to the several valves. The floating-lever 43 also partakes of the motion of the low-pressure 35 cross-head 50 transmitted from the latter by a pin 51, rock-arm 52, rock-shaft 53, link 54 fast on said rock-shaft, block 55 in said link, and rod 56 extending from the block to the floating-lever 43. A substantial duplicate 40 57 of the floating-lever 43 receives the combined motion of the cross-heads 40 and 50 by a pin 58 on the cross-head 40, and a link 59 on the rock-shaft 53, whereby the igniters 33 at opposite ends of the cylinder are operated.

45 The low-pressure engine 25 may be an ordinary engine of the steam-engine type, and its distributing-valve 60 is operated by a floating-lever 61 receiving the combined motion of the two cross-heads. The motion 50 of the low-pressure cross-head 50 is transmitted from rock-arm 52, and that of the high-pressure cross-head 40 is transmitted from the pin 58 thereon by way of rock-arm 62, rock-shaft 63, link 64 fast on said rock-shaft, and a block 65 in said link connected with the floating-lever 61 by a rod 66.

The above form of valve-gear allows for a longer or shorter cut-off according to the load on the engine, and for reversing the engine to run in either direction. The cut-off is regulated both automatically and by hand. For automatic regulation a centrifugal governor 67 is geared to the shaft 20 and through the angle of a link 68 it controls the position of a 65 clutch-sleeve 69 splined to a screw 70. By

clutching this sleeve to either one of two oppositely-rotating gears 71, 71, the screw is rotated in one direction or the other through a stationary nut 72 and hence varies the angular position of the lever 73 attached to a rock-shaft 74. Through connections 75, 76, 77, this rock-shaft shifts the block in the igniter-link 59 and varies the time of the ignition in the high-pressure cylinder. It also varies the travel of the admission-valves 75 78 and 79 of the air- and gas-compressors 27 and 28. These valves are operated by a link 80, one end of which is moved by an eccentric 81 on the shaft 20, and the other end by a lever 82 from the cross-head 83 of the compressors. The eccentric 81 is capable of slipping around the shaft 20 up to either one of two stops, according to the direction of rotation of the shaft, so that the eccentric automatically assumes the proper position 85 corresponding to the direction of rotation. The block 84 in link 80 is shifted by a rod 85 and rocker 86 from the rock-shaft 74 under control of the governor. By thus varying the time of ignition and the intake of the 90 compressors automatically in accordance with the load on the engine, the effort of the engine is adapted to the amount of the load. Such variation may also be performed by hand through a hand-lever 87 attached to the 95 rock-shaft 74. I have also shown the motion of rock-shaft 74 transmitted to the link-block 65 for the low-pressure valve through a floating-lever 88, rod 89 and connections. Reversing is performed through a hand-lever 100 90 attached to a rock-shaft 91 and having suitable connections with the link-block 55 for the high-pressure admission and exhaust valves and with the link-block 65 for the low-pressure distributing-valve. The igniters 33 are designed to operate substantially at dead center, but may be moved either side thereof through the hand-lever 87. Owing to the time required for combustion, initial inflammation of the charge at dead 105 center would give a maximum pressure of explosion somewhat after dead-center, the charge meanwhile continuing to enter. When reversal occurs by movement of the hand-lever 90 the gas suction is shut off by stop-valve 92 in the gas-compressor suction pipe connected with said hand-lever, so that the engine at first operates under compressed air and later by explosion. The valve 92 opens on both sides of mid-gear position to permit 110 115 this action.

Motion is taken off from the rock-shaft 45 for a pair of water spray pumps 93, delivering to opposite ends of the high-pressure cylinder 24 through sprayers 94 (Figs. 1 and 7), 125 whereby the burned gases are cooled and the water-sprays evaporated to make steam. As the exhaust in the present invention goes into the low-pressure cylinder the water is made useful as a heat carrier from the high- 130

pressure cylinder, later operating as an expansive working agent in the low-pressure cylinder. The amount of water in the sprays, being subject to the same regulation as the combustible charge, is proportioned to the charge, and the resulting steam will be superheated to a fairly constant degree.

The cooling-chamber 37 is composed of a casing 95 in the bottom of which is a pool of water 96 automatically maintained at a constant level by a suitable level-controller 97 (Figs. 1 and 2) and immersing the lower end of the high-pressure exhaust pipe 36 which is provided with perforations. From the upper end of this cooling-chamber the supply-pipe 98 for the low-pressure engine 25 departs and carries a mixture of steam and gases to operate the latter. From engine 25 an exhaust-pipe 99 leads to a feed-heater 100 for supplying the cooling-chamber 37 and the water spray pumps 93.

In operation the high-pressure engine 24 takes compressed air and gas from the compressors 27 and 28 at a moderate pressure, say up to 100 lbs. per square inch, or a higher pressure if the engine is properly designed therefor, and explodes the mixture, doing work on the shaft 20 and exhausting the products of combustion into the cooling-chamber 37. Here they are quenched in water, and their high-temperature heat is changed for the more suitable large-entropy heat of steam, which gives a mixture of working gases and steam suitable for transmission to the low-pressure engine 25 and adapted to perform a large part of the total work therein on shaft 20. The steam is preferably superheated to a moderate degree, which may be done automatically and in a stable manner in its passage upwardly around the outside of the hot exhaust-tube 36 within the cooling-chamber 37. Superheating may also be performed by by-passing a portion of the hot gases, unquenched, over the surface of the pool of water.

In Figs. 8 to 12 inclusive, I show a modification in which the high-pressure engine is disconnected from the low-pressure engine and the latter is in the form of a turbine.

24 indicates the high-pressure engine of the same general type as the one already described, but having its piston directly connected through a straight-line connection with the pistons of the air- and gas-compressors 27 and 28. Exhaust of the products of combustion occurs under pressure from engine 24 through exhaust-pipe 36 to the cooling-chamber 37, in the lower part of which the exhaust-pipe is shown as extended in a series of lateral open-ended perforated branches 101 whereby the intermittent puffs of gas are afforded ready expansion and collapse under a moderate head of water.

97 is the automatic water-level controller. From the cooling-chamber 37 the combined

steam and gases pass through delivery-pipe 98 to the low-pressure engine 25 of the turbine type. The only power-transmitting connection in this case between the high-pressure and low-pressure departments is of a fluid nature, and the low-pressure engine is contrasted with the high-pressure engine in being of the constant-pressure variable torque type, and also shown as operating at a nearly constant speed. In this case I have further represented a pressure-control for maintaining a substantially constant pressure in the supply pipe of the turbine. From the exhaust-pipe 36 of the high-pressure motor a pipe 102 extends to the lower side of the diaphragm 103, shown in detail in Fig. 12, on whose upper side is the pressure of the atmosphere and a spring 104. A rod 105 extends from said diaphragm to the floating-lever 106, connected by a rod 107 with the valve 108 of a hydraulic cylinder 109 whose piston is attached to the block 110 of the link 111 operated by an eccentric 112 on the high-pressure engine shaft. From one side of this block connections extend to the admission and exhaust valves 31, 32 of the high-pressure engine 24, while from the other side of said block connections extend to the igniters 33. In this manner, by controlling the effort of the primary engine 24 through diaphragm 103, the pressure of the exhaust from the high-pressure cylinder, and hence of the supply for the low-pressure cylinder, is maintained practically constant. An auxiliary link 113 transmits motion to the piston of an oil-pump 114 adapted to furnish oil fuel instead of, or in addition to the gaseous fuel, and the block of this link is subject to the pressure-control just described. This pump draws from an oil tank 115 and delivers to a reservoir 116 and thence to an automatic carbureter 117 of ordinary type such as a float-feed carbureter. The excess oil overflows and returns to the suction side of the pump through a pipe 118. The air supply for compressor 27 divides and goes partly through pipe 119 to the carbureter 117, and partly through pipe 120 directly to the high-pressure engine 24. Both of these branch pipes have coolers 121, 122, whereby the compression heat is abstracted so as to avoid any danger of preignition at high compression pressures although as already stated, the fluids are kept apart until just before ignition, so that the intercooling is less necessary in this case than it would be where the exploding engine is of internal-compression type, like the Otto. In the case of burning solid fuel the gas-compressor and oil-pump might be dispensed with or used in an auxiliary capacity, and in that case the carbureter 117 would become a gas-producer operating at superatmospheric pressure, provided with suitable arrangements for retaining this pressure during fuel feed, ash re-

moval, etc. Such a gas-producer might be constructed as disclosed in the joint patent of myself and E. P. Noyes, No. 893,192.

The turbine is shown with a throttling speed-governor, 123 being part of an ordinary centrifugal shaft-governor (conventionally represented) acting on a throttle-valve 124 in the pipe 98 whereby the speed of the turbine is maintained substantially constant. This control is extended from the governor through a rod 125 to a valve 126 in a by-pass pipe 127 for by-passing air from the air-compressor 27 around the high-pressure engine 24 into the turbine, where it performs work. Interposed in the pipe 127 is a diaphragm chamber 128 under a diaphragm 129 similar to the diaphragm 103 and attached to the same rod 105. A valve 130 in pipe 127 between the compressor and the diaphragm is adjusted to an opening intermediate between the maximum and minimum openings of the governor valve 126, so that when the latter increases its opening, the pressure below the diaphragm will be diminished and vice versa. Therefore the speed-governor 123 controls the pressure under the diaphragm 129 and hence (by varying the speed of engine 24) varies the performance of the compressors in accordance with the load on the turbine 25'. It also diverts excess volumes of compressed air into the turbine when the load falls off and speed tends to increase.

I have further carried out the idea of adapting the form of compressor to the type of motor which drives it, by connecting a fan air-compressor 131 (shown as a plural-stage fan) to the shaft of the turbine 25' and connecting its delivery-pipe 132 with the suction of the reciprocating air-compressor 27. The fan-compressor handles the initial large volumes of air and raises them to a moderate pressure to feed the reciprocating compressor whereby a portion of the duty is removed from the latter or the reciprocating compressor pressure is raised. In starting the prime motor, the compressor draws air through the fan 131 while the low-pressure motor is at rest, but any other suitable arrangement for starting may be adopted and the fan altogether omitted if desired. The low-pressure motor in this disengaged arrangement may also, as already stated, be of the reciprocating type, and the automatic governing can be omitted or modified.

Broadly speaking, my invention is not restricted to the use of a Lenoir-type motor for the high-pressure member, since most if not all of the principal types of intermittent cylinder-combustion motors may be compounded in accordance with the principles herein disclosed. Where the low-pressure motor is disengaged, as just described, the device for evaporating water by contact of the hot gases therewith under pressure, whether by

the water-pool method or by pump-injection or a suitable equivalent, and automatically maintaining a stable degree of superheat in the manner which I have described or on similar principles, assumes a special and useful aspect as a transmitting expedient, for while the superheating of the steam in the common-drive type (Figs. 1 to 7) may vary widely or be nearly absent without inflicting great inconvenience or heat-loss, in a moderately long pipe it is important to avoid condensation on the one hand or excessively high and easily-lost temperatures on the other. This expedient makes it possible to operate powerful disengaged motors by means of hot gases discharged under pressure from an internal-combustion motor, which I believe has never before been proposed.

I claim:

1. In a compound internal-combustion engine, the combination of an internal-combustion high-pressure motor, a low-pressure motor operated by the pressure of the discharged gases from said high-pressure motor, and devices subject to a common control for coincidentally varying the admission of said gases to the low-pressure motor and the supply of combustible mixture to the high-pressure motor to effect a parallel increase and decrease in the power of said motors.

2. In a compound internal-combustion engine, the combination of an internal-combustion high-pressure motor adapted to discharge against a substantially back-pressure, a low-pressure motor, a pipe connecting the two for supplying the high-pressure-discharge gases to the low-pressure motor to operate the latter, and automatic regulating devices governing the inlets of the respective motors and responsive to the load on the low-pressure motor for jointly controlling the power of the motors.

3. The combination of an intermittent-combustion high-pressure motor, a disconnected low-pressure motor operated by the pressure of the gases discharged from said high-pressure motor, and means controlled by said pressure for automatically regulating the speed of the high-pressure motor.

4. The combination of an intermittent-combustion high-pressure motor, means for compressing air to charge said motor, a variable-intake low-pressure motor operated by the pressure of the gases discharged from the first motor, and means controlled automatically according to the demand of the low-pressure motor for passing unburned compressed air from the compressor to the low-pressure motor.

5. The combination of a high-pressure internal-combustion reciprocating motor, a compressor to charge said motor and driven thereby, a disconnected low-pressure turbine motor operated by the gases discharged from

said high-pressure motor, and a rotary fan-compressor operated by the turbine motor for charging the first-said compressor.

6. The combination of an intermittent-combustion high-pressure motor adapted to discharge its gases against a substantial back-pressure, a disconnected low-pressure motor receiving and driven by said gases, a pressure-transmitting pipe connecting the two, and a device for minimizing heat-loss and condensation in the transmitting pipe,

said device comprising means for vaporizing water by contact with the transmitted hot gases and stably superheating the resulting steam by the heat of said gases.

Correction in Letters Patent No. 926,134.

It is hereby certified that in Letters Patent No. 926,134, granted June 29, 1909, upon the application of Sidney A. Reeve, of Worcester, Massachusetts, for an improvement in "Compound Internal-Combustion Engine," an error appears in the printed specification requiring correction, as follows: In line 98, page 4, the word "substantially" should read *substantial*; and that the said Letters Patent should be read with this correction therein that the same may conform to the record of the case in the Patent Office.

Signed and sealed this 13th day of July, A. D., 1909.

[SEAL.]

C. C. BILLINGS,
Acting Commissioner of Patents.

said high-pressure motor, and a rotary fan-compressor operated by the turbine motor for charging the first-said compressor.

6. The combination of an intermittent-combustion high-pressure motor adapted to discharge its gases against a substantial back-pressure, a disconnected low-pressure motor receiving and driven by said gases, a pressure-transmitting pipe connecting the two, and a device for minimizing heat-loss and condensation in the transmitting pipe,

said device comprising means for vaporizing water by contact with the transmitted hot gases and stably superheating the resulting steam by the heat of said gases.
